UNITED STATES PATENT OFFICE

FRANK E. HERR, OF LANCASTER, PENNSYLVANIA

OIL BURNER

Application filed March 17, 1930, Serial No. 436,605, and in Canada September 26, 1929.

This invention relates to improvements in oil burners, and it consists of the constructions, combinations and arrangements herein described and claimed.

5 One of the outstanding objects of the invention is to provide an oil burner in which all of the elements essential to the pumping of the oil from a storage tank, supplying the air, producing the mixture and guarding 10 against both flooding and excessive air pressures are combined in one unit which can be allocated as a unit in assembling the oil burner without disassembling, distributing or 15 otherwise affecting any of the foregoing elements.

Another object of the invention is to provide a unitary control tank in which the foregoing elements are assembled, another outstanding purpose being the elimination of 20 all piping between the elements with the consequent elimination of air and oil leaks and the absence of friction which would be engendered by short bends if piping were used, to the ultimate ends of simplicity in design 25 and construction, and economy with a marked increase of efficiency in operation.

A further object of the invention is to improve the cover of the control tank to the extent of incorporating in it both the necessary air and oil conduits as well as making 30 it the mounting for a number of the principal valves.

Other objects and advantages will appear in the following specification, reference being had to the accompanying drawings, in which:—

Figure 1 is a plan view of the improved oil burner assemblage in which the improved control tank is the outstanding feature.

40 Figure 2 is a plan view of the control tank from which the cover has been removed.

Figure 3 is a cross-section taken on the line 3—3 of Figure 1.

45 Figure 4 is a longitudinal section taken on the line 4—4 of Figure 1.

Figure 5 is a longitudinal section taken on the line 5—5 of Figure 1.

50 Figure 6 is a cross-section taken on the line 6—6 of Figure 1.

55 Figure 7 is a detail cross section taken on

the line 7—7 of Figure 1, particularly illustrating the location of the air conduit in reference to the air and oil suction valve.

Figure 8 is a cross section taken on the line 8—8 of Figure 7, illustrating how the air and oil conduits join at the foregoing valve.

This invention is an improvement on an oil burner disclosed in an application for United States patent filed January 19, 1929, by F. E. 60 Herr, Serial No. 338,622 and is based directly on an application filed by F. E. Herr in Canada September 26, 1929, Serial No. 355,702. The features especially emphasized in the instant application are the cover of the control 65 tank and the air and oil valve which coacts with certain air and oil conduits incorporated in the cover for the purpose of regulating these constituents.

Figure 1 illustrates a burner apparatus of 70 which the invention is a part which comprises the following:—A base 1, electric motor 2, fan or blower 3, burner 4 and control tank 5. In the latter a shaft 6 (Fig. 1) is the common 75 driver of the fan 3 and the rotor 7 (Fig. 4) of a pump 8 formed within the tank 5. The housing 9 of this pump is an integral casting with the body 10 of the control tank (Figs. 3 and 4).

A partition 11 (Figs. 2 and 5), also cast 80 integrally with the housing 9 of the body 10 divides the control tank into a primary or pumping chamber 12 and a secondary or air and oil chamber 13. It is in the latter that the constituents of the combustible fluid are 85 finally assembled and from which they are conducted by means of a spray pipe 14 (Fig. 1) to the burner 4. This may be any known burner but particularly either the burner of F. E. Herr, disclosed in an application filed 90 August 9, 1928, Serial No. 298,568 or in an application filed March 10, 1930, Serial No. 434,642.

Situated in the primary or pumping chamber 12 is a manifold 15 (Figs. 2, 3, 5 and 6) 95 which has connection at one end with the intake 16 of the pump 8 (Figs. 2 and 6). The major part of the manifold is in the form of a U (Figs. 3 and 6), the point of entry 17 being situated well above the oil level in the chamber. 100

ber 12 for the admission of air, while the submerged part has a hole 18 for the admission of oil. The suction of the pump draws air and oil into the manifold respectively at the entry 17 and hole 18.

Extending from the pump 8 and on the opposite side of the partition 11, hence in the secondary chamber 13, is a discharge pipe 19 (Figs. 2, 3 and 6). Air and oil drawn in at the manifold 15 in the primary chamber 12 is discharged at the pipe 19 into the secondary chamber 13. The discharge will be in the form of a mixture, but the constituents will separate in the chamber 13 so that there will be a stratum of oil (Figs. 3 and 6) and a stratum of air above it.

The constituents are again mixed by a triple valve 20 of which the valves 21, 22 actually accomplish the mixing of the air and oil. The third valve 23 is a relief valve which controls the escape of air from the secondary chamber 13 under excessive pressure. The triple valve is the special subject of a United States application filed by F. E. Herr, March 17, 1930, Serial No. 436,606.

Oil is pumped into the primary or pumping chamber 12 in the following manner and it is in this connection that the description of the specific invention occurs:—An oil pipe 24 (Fig. 1) leads from an oil storage tank (not shown) to a point of connection with the conduit 25 of an air and oil suction valve 26 (Fig. 5). Both the conduit and the casing 27 of the valve are cast integrally with the cover 28 of the control tank 5. The casing 27 is an upstanding cylinder (Figs. 3 and 5) which is in direct communication with the conduit 25 through an oil port 29 (Figs. 5 and 8), and with the primary chamber 12. It has a screw or other cap 30 by which access to the interior may be had from the top.

A port 31 (Figs. 3, 5 and 8) represents the terminal at the valve 26 of an air conduit 32 which is cast integrally with the cover 28. The casting of the air conduit is in common with the casing 27 and a block 33 (Figs. 1, 3 and 4) by which the triple valve 20 is carried. This air conduit has a hole 34 at which atmospheric air is admitted prior to introduction into the primary chamber 12 past a valve member 35 which is reciprocable in the casting 27.

The air conduit 32 is also the place where air under excessive pressure in the secondary chamber 13 is discharged. The discharge occurs past the relief valve 23 as already indicated. This relief valve consists principally of a ball 36 pressed toward its seat upon an air opening 37 by a spring 38. The tension of the spring is adjustable so that the ball 36 will respond to any desired pressure.

It is important to note that the air conduit 32 has the special purpose of preventing the collection of an oil film on top of the cover 28.

The air escaping from the chamber 13 always

carries particles of oil in suspension. If the air were permitted to escape directly to atmosphere this oil would collect around the escape opening and on top of the cover. But by causing it to discharge into the conduit 32 all suspended oil will settle on the bottom of the conduit whence it is automatically drawn back into the chamber 12 by the vacuum formed in that chamber, and acts as an oil seal on the walls of the valve member 35. This member fits free in the casing 27 and must have the oil seal to prevent air leakage. Any oil collecting in the conduit 32 will run toward the casing 27 where it will lubricate the valve member 35 and ultimately drip into the chamber 12. The use of the air conduit 32 avoids any more or less troublesome arrangement of piping for accomplishing the same purpose. By virtue of incorporating the air conduit within the cover 28 a direct return of oil from the triple valve 20 to the valve 26 is afforded, the principal advantage being the prevention of oil leakage or the dissemination of oil fumes throughout the building.

Reverting now to the valve member 35 it is to be observed that this comprises a sleeve (Figs. 3, 5 and 8) which has an oil inlet 39, an oil outlet 40 and an air inlet 41. The oil inlet 39 is registerable with the oil port 29 and it is at this point where oil is admitted to the primary chamber 12 by way of the outlet 40. The air inlet 41 is registerable with the port 31 and it is at this point that air is admitted to the chamber 12 also by way of the outlet 40.

The valve member 35 has a stem 42 depending from the otherwise solid bottom at which stem the link 43 of a primary float 44 is connected through the medium of the rocker 45 of the latter. The rocker is pivotally attached to a support rod 46 depending from the cover 28. Thus far it will be seen that the removal of the cover will expose the working parts of the valve 26 to view so that any necessary inspection or repair may be made with the utmost care.

An approximately normal working position of the float 44 occurs when the level of oil in the primary chamber 12 is sufficiently high to withdraw the valve member 35 from the casing 27 until the solid upper portion of the sleeve covers the oil port 29 and uncovers the air port 31 at the air inlet 41. Lowering of the float 44 from the position stated will cause covering of the air port and uncovering of the oil port. The adjacent ends of the inlets 39 and 41 are approximately on a line with each other so that after the float 44 once assumes the foregoing normal working position there will be but a slight variation of the float in either direction before there will be an admission of either air or oil depending upon the particular need.

The level of oil in the secondary chamber

13 is kept approximately uniform in the following manner:—An oil relief valve 47 (Figs. 2, 3 and 6) is capable of being turned to opening and closing positions in reference to an oil pipe 48 by which it is carried, through the medium of a secondary float 49. The pipe 48 has communication with a cross-over passage 50 (Figs. 1 and 6). This passage is cast integrally with the cover 28. 10 One end has a boss 51 (Fig. 6) in which the oil pipe 48 is fitted to establish its communication with the secondary chamber 13. The other end of the passage has an outlet 52 into the primary chamber 12. The rising of the oil in the chamber 13 to an excessively high level causes the opening of the valve 47 whereupon the pressure of air drives the oil through the pipe 48 and cross-over passage 50 into the chamber 12 without disturbing 20 the atmospheric condition within the latter.

Again it is to be observed that this particular phase in the control of oil is accomplished without adding any external pipes to the control tank. The cross-over passage is incorporated in the cover 28 and since no external joint occurs it follows that there can be no leakage of oil around the cross-over passage.

It can now be understood that the action of 30 the pump 8 draws in oil and air separately at the openings 39 and 41 (Fig. 5) and that these constituents are transferred to the secondary chamber 13 as a mixture by way of the manifold 15 and discharge pipe 19 (Fig. 2). The 35 level of oil in the primary chamber 12 as well as the supply of air is subject to automatic control by the float 44 (Fig. 5) and the valve member 35.

On a similar principle, the level of oil in 40 the secondary chamber 13 is automatically controlled by the float 49 (Fig. 6) while air under excessive pressure is released from the secondary chamber by the relief valve 23 (Fig. 3).

45 These operations are not desired to be emphasized in this application since the cover 28 is the important factor. It has been brought out already that the conduits 25 and 32 as well as the cross-over passage 50 are 50 permanently incorporated in the cover so as to be inseparable therefrom. There are no unnecessary joints at which oil leakage can occur, the only necessary pipe joint occurring where the spray pipe 14 has connection with 55 the triple valve 20 and the feed pipe 24 is connected at one end of the conduit 25.

The two floats 44, 49 depend from the cover (Figs. 3 and 6), hence it follows that the removal of the cover will not only permit 60 an unobstructed view of the interior of the tank body 10 but also render the working parts of the various valves accessible for such inspection or repairs as may be needed.

While the construction and arrangement 65 of the improved oil burner, is that of a gen-

erally preferred form, obviously modifications and changes may be made without departing from the spirit of the invention or the scope of the claims.

I claim:—

1. A control tank having a partition dividing it into primary and secondary chambers, a cover for the tank serving both chambers in common, a pipe having a relief valve for relieving the secondary chamber of excessive fluid under pressure, and a cross-over passage incorporated in the cover with the inlet of which the pipe is connected, said passage having an outlet discharging into the primary chamber. 70

2. A control tank having a partition dividing it into primary and secondary chambers each to contain air and oil, a cover for the tank serving in common for both chambers, a cross-over passage incorporated in the cover having an inlet at the secondary chamber and an outlet at the primary chamber, a pipe depending from the inlet into the oil in the secondary chamber, a relief valve in the pipe for opening and closing the cross-over passage to the secondary chamber, and oil level-operated means in connection with the valve for setting its open and closed positions. 75

3. A control tank having a partition dividing it into primary and secondary air and oil chambers, a cover for the tank serving in common for both chambers, a valve casing embodied in the cover having a movable valve member by the action of which the flow of air and oil of the primary chamber is controlled, an air pressure relief valve for the secondary chamber, and an air conduit into which said valve opens having a hole for the relief of air, being incorporated in the cover with the casing for the delivery of condensed oil thereto in order to lubricate the walls of the casing and seal the valve member. 90

4. A control tank having a partition dividing it into primary and secondary chambers each to contain air and oil, a common cover for the chamber having an air opening communicating with the secondary chamber, a valve block on the cover carrying a relief ball valve arranged to seat on the opening, a valve member associated with the primary chamber for controlling the admission of air and oil thereto, a casing incorporated in the cover in which said valve member is movable, and a conduit also incorporated in the cover connecting the block and said casing, having a hole for the discharge of air escaping past the relief ball valve but serving to confine condensed oil and conduct it to the casing for the lubrication thereof and sealing of the valve member. 100

5. In combination with a control tank divided into primary and secondary chambers, and a cover for the tank serving in common with both chambers and carrying the follow- 115 120 125 130

ing elements to constitute the cover a separable unit; an air and oil suction valve and its operating means depending from the cover in the primary chamber, an oil relief valve and its operating means depending from the cover in the secondary chamber, an air relief valve associated with the secondary chamber, a casing in which the suction valve is operable, separate conduits leading from the casing one being for the oil supply the other joining the air relief valve, and a cross-over passage establishing communication between the oil relief valve and the primary chamber.
